DEVICE FOR LIMITING THE MOVEMENTS
OF THREAD GUIDE BARSWoldemar Heinitz, Chemnitz, Germany, assignor
to Schubert & Salzer Maschinenfabrik Aktien-
gesellschaft, Chemnitz, GermanyApplication November 21, 1935, Serial No. 50,943
In Germany November 23, 1934

3 Claims. (Cl. 66—126)

The present invention relates to flat knitting machines adapted to produce plated work and is more particularly concerned with a device for limiting the movements of the thread guide bars.

The devices for limiting the movements of thread guide bars known hitherto are constructed as locking devices, operating on the thread guide bars at the end of their movement, that is to say, they are formed as recoil preventing means, acting at the moment the thread guide bars reach the end position. In constructing locking devices of this kind great care must be taken to obtain highest precision, but even then the known locking devices are not absolutely reliable, if high speed platings are carried out, as the locking action is effected only in the very last moment the thread guide bar strikes the stop, i. e. in the moment of recoil of said bar.

Compared with all known locking devices of this character, the device according to the present invention has the great advantage, that, with always uniform distance between the thread guides, exact limitation of the movement of the thread guide bar is obtained under all circumstances with the simplest possible means which simultaneously prevent recoil of the bar.

To obtain this object, locking members, moved in the same direction as the thread guide bars, strike, in the same direction of movement, against lever arms carried by shafts upon which locking arms are mounted adapted to engage behind projections fixed upon the thread guide bars.

These locking members, sliding beneath the lever arms, take up the recoil of the thread guide bars in the moment the recoil can not longer have any effect upon the thread guide bar.

According to the present invention, a locking member is used for each of the thread guide bars, that is to say, for each of the ground thread guide and the plating thread guides a particular locking member is provided. The locking members are arranged in staggered relation to each other, so that the thread guides are simultaneously locked in spite of the different mutual distances from each other. The lever arms are mounted on shafts carried by the devices for limiting the movements of the thread guide bars, so that, when the positions of said limiting devices are altered by means of a spindle having right-hand and left-hand threads, the locking arms also are always adjusted in exactly the same manner. Connected to the devices for limiting the movements of the thread guide bars

are cam members effecting the connection and disconnection of the brakes. The position of these cam members also is altered with the adjustment of the devices for limiting the movements of the thread guide bars.

In the accompanying drawings one embodiment of the invention is shown by way of example.

In these drawings:

Fig. 1 is a perspective view of the device according to the invention, showing as much of the knitting machine only as is necessary to understand the operation of the new device,

Fig. 2 shows a broken away side elevation and Figs. 3-8 are detail views, showing the individual parts of the device in different working positions.

For explaining the construction and operation of the device according to the invention a flat knitting machine, having two thread guide bars, 20 is chosen in the middle part of which the devices for limiting the movements of the thread guide bars in both directions of travel are arranged. Of course, if the thread guide bars would strike against stops provided at the ends 25 of the machine, the devices for limiting the movements of said bars and therefore the locking devices would be arranged at both ends of the machine. The devices for limiting the movements of the thread guide bars are, by way of 30 example, shown in connection with plating thread guides. It is, however, understood that the invention may also be used for limiting the movements of other thread guides.

Mounted upon a bar 1, journaled in the frame 35 of the knitting machine, not shown in the drawings, and kinematically connected to the slur bar, also not shown, are two blocks 2 and 2', one for each direction of movement of the thread guides. The block 2 carries the locking members 40 3, 4 cooperating with the device for limiting the movements of the thread guide bars 5, 6 in one direction of their travel and the block 2' carries the two locking members 3', 4' cooperating with the device for limiting the movements of the two thread guide bars 5, 6, in the other direction of their travel. The portions 7, 8 and 7', 8' respectively of the locking members 3, 4 and 3', 4' are arranged in front are higher than the rear portions 9, 10 and 9', 10' respectively and are connected with the portions 7, 8 and 7', 8' respectively by inclined surfaces 11, 12 and 11', 12' respectively. A number of locking members equal 55

to the number of thread guide bars to be locked is always provided.

Shiftably arranged upon a supporting bar 13 fixed in the frame of the machine are the devices 5 14 and 14' for limiting the movements of the thread guide bars 5, 6 and a spindle 15 having right-hand and left-hand threads serves to adjust the devices 14 and 14' which for this purpose are provided with corresponding female 10 threads.

As all parts are provided in the same arrangement and operate in the same manner for both directions of movement, the elements shown at the right hand portion of Fig. 1 only are described 15 below, the corresponding elements shown at the left hand portion of Fig. 1 being designated with the same reference numbers provided with an index.

The device 14 for limiting the movements of 20 the thread guide bars 5 and 6 in one direction carries bearings 16 in which a hollow shaft 17 is journaled with slight friction. Fixed upon one end of the hollow shaft 17 is a lever 18 carrying a roller 19 which lies in the path of the 25 locking member 3 and is adapted to slide upon the upper surface 7 of the latter. At the other end of the hollow shaft 17, a locking arm 20 is adjustably fixed by means of a screw 21. The locking arm 20 is adapted to engage behind a 30 projection 22 fixed upon the thread guide bar 5.

A shaft 23 journaled with slight friction in the hollow shaft 17 extends at both ends beyond the hollow shaft 17. Fixed upon one end of the shaft 23 is a lever arm 24 carrying a roller 25. 35 The roller 25 lies in the path of the locking member 4 and is adapted to slide upon the upper surface 8 of the latter. Upon the other end of the shaft 23 a locking arm 26 is adjustably fixed by means of a screw 27. The locking arm 26 is 40 adapted to engage behind a projection 28 fixed upon the thread guide bar 6. Linked to the lever arm 18 is a pawl 29 which lies in the path of a stop 30 fixed to the block 2 carrying the locking members 3, 4. The pawl 29 is adapted to bear 45 against a projection 31 provided at the free end of the lever arm 18 and serving as a stop. A finger 32 at the device 14 serves to limit the movement of the thread guide bars 5, 6, and against this finger 32 the projections 22 and 28 fixed 50 upon the bars 5 and 6 respectively are adapted to strike.

Fixed to the device 14 for limiting the movements of the thread guide bars 5, 6 is a bar 33 the bent arm 34 of which is connected to a cam 55 member 35 guided in a slot 36 of a bar 37. The bar 37 is arranged between the thread guide bars 5, 6 and the brake bar 38. By means of the cam member 35 the arm 39 connecting the thread guide bar 5 to the brake mechanism, and by 60 means of the cam member 35', the arm 39', connecting the thread guide bar 6 to the brake mechanism, may be lifted.

If the thread guide bars 5, 6 and the bar 1 move in the direction of the arrow x (Figs. 1 and 65 3), the projection or stop 30 strikes, at the end of the travel, against the pawl 29 mounted on the lever arm 18. As the pawl 29, bearing against the projection or stop 31, is prevented from giving way, striking of the stop or projection 30 70 against the pawl 29 results in swinging the lever arms 18 and 24 into the range of the locking members 3, 4. Upon further movement of the bar 1, the lever arms 18 and 24 are turned by the locking members 3 and 4 and thereby the shafts 75 17 and 23, carrying said lever arms 18 and 24

respectively, are turned, whereby the locking arms 20 and 26, mounted at the other ends of the shafts 17 and 23 respectively, are swung downwardly into the path of the stops 22 and 28 respectively fixed upon the thread guide bars 5 and 6 respectively (Figs. 1 and 4).

On further movement of the bar 1, the lever arms 18 and 24 are lifted until they rest upon the upper surfaces 7 and 8 of the locking members 3 and 4 respectively, whereby the thread guide 10 bars 5 and 6 are locked by means of the locking arms 20, 26, thereby preventing any recoil (Fig. 5).

At the end of the movement of the slur bar to which the locking members 3, 4 are kinematically 15 connected the pawl 29 has been moved out of the range of the stop 30 and drops downwardly (Fig. 6).

During this event of movement, the arm 39 of the brake mechanism is disconnected by the 20 cam member 35 in the moment in which the locking members 3, 4 come into the range of the lever arms 18, 24.

After reversal of the direction of the movement of the locking members 3, 4 the arm 39 of 25 the brake mechanism is engaged again, so that the thread guide bar 5 may be shifted in the reverse direction. During the movement of the thread guide bars 5, 6 in the direction of the arrow y (Fig. 6), the stops 22, 28, fixed to said 30 bars, effect rising of the locking arms 20, 26, whereby the shafts 17, 23 are turned, so that the lever arms 18, 24, fixed to the shafts 17, 23 respectively, are moved into the position shown in dash- and dotted lines in Fig. 6. The lever 35 arms 18 and 24 running upon the inclined surfaces 11 and 12 respectively, are moved again into their position of exit, shown in Fig. 7, in which they remain by a corresponding braking effect 40 exerted upon their shafts 17 and 23 respectively. As soon as the pawl 29 comes into the range of the stop 30 it is, as shown in Fig. 8, swung and then drops back into its vertical position. The individual parts now occupy again the position 45 shown in Fig. 3 and the cycle of operation is repeated as soon as the bar 1 is moved again in the direction of the arrow x (Fig. 1).

As the cam members 35 and 35', disengaging the arms 39 and 39' respectively from the brake mechanism, are, by means of the bars 33 and 33' and the arms 34 and 34', kinematically connected to the devices 14 and 14' respectively for limiting the movements of the thread guide bars 5 and 6, adjustment of the devices 14, 14' automatically effects a corresponding adjustment of 50 the cam members 35 and 35'. 55

What I claim is:

1. A device for limiting the movement of thread guide bars in flat knitting machines comprising a plurality of blocks adjustably mounted on a supporting bar and each provided with a projection extending into the path of travel of said thread guide bars, shafts mounted upon said blocks, locking arms adjustably connected to said shafts and adapted to cooperate with stops on said thread guide bars, lever arms fixed to said shafts, a roller carried by each of said lever arms, a slidably arranged bar moved in accordance with said thread guide bars, locking means carried by said slidably arranged bar and cooperating with said lever arms for moving said locking arms into and out of engagement with said stops on said thread guide bars, the arrangement being such that said locking arms, by their engage- 70 75 70 75 75

ment with said stops on said thread guide bars, prevent recoil of the latter bars.

2. A device for limiting the movements of thread guide bars in flat knitting machines comprising a plurality of blocks adjustably mounted on a supporting bar and each provided with a projection extending into the path of travel of said thread guide bars, bearings provided at the upper surface of each of said blocks, a hollow shaft frictionally journaled in said bearings of each of said blocks, a locking arm adjustably connected to one end of each of said hollow shafts and adapted to cooperate with a stop attached to one of said thread guide bars, a lever arm fixed 10 to the other end of each of said hollow shafts, a roller carried by said lever arms, a slidably arranged bar moved in accordance with said thread guidebars, locking members, one for cooperation with each of said lever arms, carried by said 15 20 25 30 30

for limiting the movement of said pawl, attached to each of said lever arms, a stop carried by each locking means arranged in the path of said pawl, a solid shaft frictionally carried by each of said hollow shafts, both ends of each of said solid shafts projecting beyond the ends of each of the hollow shafts, a locking arm adjustably connected to one end of each of said solid shafts and adapted to cooperate with a stop attached to one of said thread guide bars, a lever 10 15 20 25 30 arm fixed to the other end of each of said solid shafts, a roller carried by each of said lever arms on said solid shaft, a second set of locking members carried by said slideable bar, an elevated operative portion and an operative portion at a lower level provided in the order mentioned one behind the other in the direction of active movement, and an inclined operative portion connecting said two operative portions on each of said second set of locking members, each of said operative portions of said second set of locking members being adapted to cooperate with the corresponding of said rollers on said lever arms fixed to said solid shafts.

3. A device as set forth in claim 2 in which cam members adapted to disconnect a braking mechanism from said thread guide bars are connected to bent bars fixed to said devices for limiting the movements of said thread guide bars.

WOLDEMAR HEINITZ. 30
